(No Model.)

H. McDERMOTT.
TOP FLAT CARD GRINDING.

No. 534,721.

Patented Feb. 26, 1895.

UNITED STATES PATENT OFFICE.

HENRY McDERMOTT, OF NASHUA, NEW HAMPSHIRE.

TOP-FLAT-CARD GRINDING.

SPECIFICATION forming part of Letters Patent No. 534,721, dated February 26, 1895.

Application filed February 20, 1894. Serial No. 500,849. (No model.)

To all whom it may concern:

Be it known that I, HENRY McDERMOTT, a citizen of the United States, residing at Nashua, in the county of Hillsborough and 5 State of New Hampshire, have made certain new and useful Improvements in Top-Flat-Card Grinders, which improvements are fully set forth and described in the following specification, reference being had to the accompanying sheet of drawings, in which—

Figure 1 is an end elevation of a grinder embodying my invention, the stand which supports the journal bearing of the grinder-roll being removed. Fig. 2 is a side elevation 15 of the same parts, with the grinder-roll stand in position. Inasmuch as the operative parts of my machine are the same at each end of the grinder I have thought it necessary to illustrate only one end of the same. Fig. 3 is 20 a cross-sectional view on line $x-x$ of Fig. 2. Fig. 4 is a sectional view through the upper end of the standard and the plate, e , said section being taken upon a line, such as is indicated at $x-x$ Fig. 1, which extends through 25 the wider part of said plate.

This invention is in the class of grinders, (used for dressing or leveling up the top-flats of carding machines) which, being attached permanently to the carding machine frame, 30 may be brought into grinding relation with the top-flats, or thrown out of operation, at will and my purpose is to provide simple and cheap mechanism which may be readily controlled and quickly adjusted.

35 In carrying into effect my invention I have dispensed with certain cumbersome levers and weights which have been used, in some instances, heretofore.

Referring now to the drawings, a indicates 40 a standard secured to the carding-machine frame and having bolted to its outer face a bracket-stand b whose upper end is formed as a journal bearing b' in which the shaft c' of the grinding roll c revolves. The upper 45 portion of standard a is reduced in thickness (as seen at a' in Fig. 2) and is formed with laterally extending arms, or ends, a^2-a^3 whose upper face, or edge, is straight throughout the greater part of its length but whose ends 50 are gradually reduced in height, as shown in Fig. 1, to provide ways on which the ends of the top-flats may be successively guided as

they approach the grinding roll c . Secured to the outer face of this reduced portion a' , by bolts $d-d'$, is a bar or plate e whose upper portion e' projects laterally and overhangs the part a' . One half, or thereabout, of this overhanging portion is reduced in thickness (as shown at e^2 Fig. 1) to receive a shoe f which is secured in place by screws f' , the screw holes in the shoe being elongated, as in Fig. 1, to permit limited vertical adjustment of the shoe, said shoe and the overhanging part of the bar or plate thus forming a way, composed of two parts which are adjustable 65 together and one of which parts is also adjustable independently of the other. I do not wish, however, to be understood as limiting myself to this particular construction of way for limiting the extent of the upward movement of the flats, as any construction of way 70 having the adjustment mentioned may be employed without departing from the spirit of the invention, whether the same consists of a shoe and a bar or plate, or of other devices. 75

When shoe f is properly adjusted its lower edge is somewhat below the lower face e^3 of the overhanging portion e' of the plate e and, preferably, parallel therewith but not necessarily so, as clearly indicated in Fig. 1. The end of shoe f immediately beneath the axial center of the grinding roll c is beveled, as at f^2 , so that as the top-flats travel in the direction indicated by arrow No. 1, said flats are 85 deflected downward and guided in a direction to grind the proper bevel or angle on the ends of the card-teeth and, to vary said angle, it is only necessary to loosen the screws f' and raise or lower the shoe f , thus varying 90 its lower level relatively to that of the fixed, overhanging, portion e' to which the shoe is clamped.

Whenever the grinding roll c becomes worn and reduced in diameter, and it is desired to 95 adjust the plate e and its attached parts, this may be readily done by loosening the nuts of bolts $d-d'$, the openings through which said bolts pass being enlarged to permit lateral adjustment and the opening of bolts d' being 100 also enlarged to permit vertical adjustment. This provision for double adjustment enables the attendant to raise the plate e without materially disturbing the end nearest the in-

clined way a^2 on which the flats first ride as they approach the grinding roll; the bolt d meanwhile serving as a fulcrum upon which the plate e may be rocked, as well as moved 5 longitudinally.

I preferably drill and tap the plate e , near the bolt d' , and insert therein a screw g whose lower end abuts the top of standard a . When it is desired to adjust plate e vertically it is 10 only necessary to ease the nut of bolt d' and set up the screw g , when the end of the plate that bears shoe f will be forced upward or, by unscrewing screw g said shoe and its support may be lowered. It will thus be seen that 15 the plate e and its attached parts may be adjusted as a whole, either vertically or longitudinally and that shoe f may be adjusted independently of the plate which supports it.

To force the card-teeth of the top-flats upward, into grinding relation with roll c , I have provided a spring-pressed rod h arranged to slide vertically in bearings i formed as parts of a bracket-frame k which is bolted to the standard a . The upper portion, or 20 head, of the rod h is made with a laterally 25 extending arm h' that is bent downward upon the side from which the top-flats approach the grinder.

It will be seen by reference to Fig. 2 of the drawings that each top-flat is formed with an extension m that may engage and ride upon the ways a^2-a^3 and also with a "heel" portion m' that engages and rides upon the arm h' of rod h . When the grinder is in operation 30 the rod h is then in its highest position and the top-flat ends m are raised from the ways a^2-a^3 until they engage and ride upon the lower faces of the overhanging portion of plate e and of the shoe f . When, on the other 35 hand, the grinder is thrown out of operation, the rod h is lowered, permitting the ends m of the flats to travel on said ways a^2-a^3 , thus allowing the card-teeth of the flats to pass under the grinder roll without engaging it.

40 To force the rod h upward I have coiled thereon a spiral spring n one of whose ends abuts the lower bearing i . The opposite (upper) end of said spring abuts a nut n' screwed upon rod h and said spring seeks constantly, 45 by reason of its expansive force, to carry the rod upward. A check nut n'' is also preferably provided to retain nut n' in position after adjustment. Loosely mounted upon the lower end of rod h is a collar o having an operating handle o' , the lower face of said col- 50

lar being formed as a cam o^2 that engages a radial pin h^2 in the rod h in such manner that when the cam-collar is partially rotated the rod is drawn downward, against the force of the spring. 55

When it is desired to bring the grinder into use it is only necessary to rock the cam o^2 into the position shown in Fig. 2 when spring n by its effort to expand, immediately forces the rod h , and top flats supported thereon, upward. 60

My described grinding device, as a whole, is believed to be quite as simple as any in use and may be quite as readily adjusted or started into action. 70

Having described my invention, I claim—

1. In a top flat card grinder, the combination with the grinding roll and its supports, and mechanism for forcing the flats upward into grinding relation with the roll, of a way 75 for limiting the extent of the upward movement of said flats, said way consisting of two parts which are adjustable together and one of said parts being also adjustable independently of the other, substantially as described. 80

2. In combination with a grinding roll and supports for the same, spring-pressed rods and cams for controlling said rods, as set forth, and ways consisting of an overhanging plate with an adjustable shoe, for limiting 85 the upward movement of the top-flats; the said plate being adjustable vertically and longitudinally to vary the position of said ways relatively to the grinding roll, as specified.

3. In a top flat card grinder, the combination with the grinding roll and its supports, and mechanism for forcing the flats upward into engagement with said roll, of an adjustable plate, and a shoe supported by said plate, 90 said shoe and plate being adjustable together and said shoe being also independently adjustable on said plate and both forming a way for limiting the upward movement of said top flats, substantially as described.

4. In a top flat card grinder, the combination with the grinding roll, and ways for the top flats, of a vertically-movable spring-pressed rod having a pin, and a rotatable collar, loosely encircling said rod and having a cam engaging said pin, substantially as described and for the purposes specified. 100 105

HENRY McDERMOTT.
